UNITED STATES PATENT OFFICE.

GEORGE N. MCKANE, OF BROOKLYN, NEW YORK.

FORM FOR WEAVING BASKETS.

Application filed August 1, 1925. Serial No. 47,535.

Among the principal objects which the present invention has in view are:—

To provide a novel collapsible basket weaving form; to provide a separable element form which may be removed from the finished work in sections; and generally to provide an improved weaving form for the manufacture of baskets having inturned overhanging sides.

10 *Drawings.*

Figure 1 is a top plan view of the assembled form;

Figure 2 is a section therethrough on the line 2—2 of Figure 1 illustrating a basket weaving applied thereover and the manner of removing the form.

Description.

20 The invention is particularly intended for use in connection with the manufacture of woven baskets wherein the sides overhang inwardly at the top.

In detail the invention comprises a pair 25 of semielliptical blocks 10 having flat opposite faces 11 spaced apart by center sections 12 and 13 to form in their entirety a circular forming block. The tops and bottoms of the semielliptical side sections 10 are made 30 flat as at 14 with the body of the sections intermediate the top and bottom being formed in rounded edge portions 15 shaped to the desired form of basket.

The central block 12 of the form is provided with a flat bottom 16 and a flat top 17, the surfaces of which are flush with the flat top and bottom surfaces of the side sections 10. The body portion of the block 12 between its top and bottom is rounded as at 18 40 to conform to the shape of the rounded portions of the side sections.

The top 17 of the center block 12 overhangs the bottom 16 and the inner edge 19 of the block terminates on an incline extending diagonally between the top and bottom as illustrated in Figure 2. The block 13 is of counterpart formation with the block 12, its relative position being reversed so that it carries a relatively small top 20 and a 45 relatively large bottom 21 between which extend the inner edge inclined face 22 adapted when the blocks are in position to engage under the inclined face 19 of the inner edge 50 of the block 12. The block 12 carries at approximately the center of its top surfaces a

recess 23 formed therein to provide a finger socket whereby the block 12 may be moved on the block 13 in the manner shown in dotted lines in Figure 2.

In the initial assembly of the separable 60 sections of the form, the side sections 10 and interposed center blocks 12 and 13 are held in assembled relation by means of a pair of attaching pins 24 passed through transverse apertures formed in the side sections and 65 central blocks adjacent the lower portions thereof whereby the sections are held in temporary assembled relation.

In weaving a basket upon the form the base matting 25 is first woven and applied 70 over the bottom of the assembled form. A disk 26 of suitable material and of the same area as the flat bottom of the assembled form is then applied over the base matting and secured to the form sections by means of the 75 fastening tacks 27. A similar disk 28 is then applied over the top of the form and secured to the sections by means of the fastening tacks 29. As the function of the disks 26 and 28 is to hold the form sections in assembled position during weaving, the anchor pins 24 are withdrawn from their engagement between the form sections and the weaving of the basket is proceeded with carrying the material 30 up around the 80 rounded side portions of the form block to the finished inturned overhanging top 31.

When the weaving is completed the disks 26 and 28 are removed from the form and an operator by inserting a finger in the recess 85 23 of the central block 12 may withdraw the block diagonally through the top of the basket over the inclined face 22 of the block 13. The block 13 may then be moved inwardly between the side sections 10 for withdrawal through the top of the basket and subsequently the side sections 10 may be moved inwardly for removal from the interior of the completed basket.

100 *Claim.*

A form for weaving articles having a flat bottom, outwardly bowed sides and a top overhanging the flat bottom, comprising a pair of semi-elliptical side sections having 105 opposed flat faces and flat top and bottom portions, a pair of center blocks disposed between said side sections to maintain said side sections in spaced relation, said center blocks having oppositely inclined meeting 110

faces for slidable relative movement, said center blocks being further provided with outwardly bowed portions conforming to the contour of said side sections at the exterior 5 of the form, said center blocks having each a flat top and bottom portion to be disposed flush with the top and bottom portions of

said side sections, and means detachably applied to the flat bottom of said form over work thereon for maintaining said sections 10 and blocks in assembled position during the weaving.

GEORGE N. McKANE.
